B. D. THOMPSON

SUCKER ROD COUPLING

Filed May 14, 1923

FIG. 1

FIG. 2

FIG. 3

FIG. 4

Inventor

B. D. Thompson.

By Adrian Dyer
his Attorney

UNITED STATES PATENT OFFICE.

BURCHARD D. THOMPSON, OF CYCLONE, PENNSYLVANIA.

SUCKER-ROD COUPLING.

Application filed May 14, 1923. Serial No. 638,782.

To all whom it may concern:

Be it known that I, BURCHARD D. THOMPSON, a citizen of the United States, residing at Cyclone, in the county of McKean and 5 State of Pennsylvania, have invented certain new and useful Improvements in Sucker-Rod Couplings, of which the following is a specification.

This invention has reference to improvements in forming connections between broken sections of what is known in the art as sucker-rods for oil well pumping gear.

These rods are used in operating the pump piston within the working barrel of the 15 pump located near the bottom of deep wells such as oil wells.

In order that sucker-rods may be conveniently handled, they are made in sections and are provided with a usual form of screw 20 couplings by means of which the several sections may be joined in alignment to the combined length desired. Where great lengths are required, the strain on the rods in the pumping operation frequently causes breakage of the rods.

When a break occurs, the several sections of rods above the point of the break have to be withdrawn from the well and disconnected at the joints as withdrawal takes place.

30 The remaining sections of rods below the point of break will have to be "fished out", a method well known in the art, which is an operation uncertain of accomplishment within a reasonable time.

35 The purpose of this invention is to avoid this "fishing job", as well as to avoid the raising of the lower sections of rods positioned below the point of break, to a point above the surface of the well, necessary to 40 replace the broken section.

With my novel device, a broken section of a sucker-rod may be coupled within the well at any given point below the surface, and when so coupled, the whole string of 45 rods may be placed in pumping operation without further delay.

This invention will be best understood from a consideration of the following detailed description taken in connection with 50 the accompanying drawings, wherein:

Fig. 1, is a central longitudinal section of the invention, together with a vertical section of the well tubing in which the invention operates.

55 Fig. 2, is an enlarged sectional view of the

invention showing the thread cutting dies and the retaining socket therefor.

Fig. 3, is a side elevation of the thread cutting dies.

Fig. 4, is a view in cross section of the 60 parts assembled in Fig. 2 shown on the lines 4—4.

Referring to the drawings, (Fig. 1) the numeral 1, designates the well tubing, 2, is the valve cage, 3, is a section of the sucker-rod attached to the valve cage, shown with parts of the rod broken away, 4, is the internally threaded half of the sucker-rod joint, 5, is the shank of the die socket adapted to be screw threaded into the joint 4, 6, 70 is the die retaining shell adapted to be screw threaded on the opposite end of die shank 5, 7 and 7' are the die members adapted to be positioned within the shell 6.

Referring more particularly to the die 75 members 7 and 7' and their retaining means as shown in Fig. 2, the die socket shank 5 is exteriorly threaded at its lower end, to engage the threaded interior of the upper end of the shell 6. The lower end of the shell 80 is formed with an inwardly extending collar 8, which is formed with its lower face beveled outwardly, forming an apex at 9 with the exterior wall of the shell 6.

The die socket shank 5 has formed within 85 its lower end, a tapering rectangular shaped recess 10, adapted to receive a correspondingly shaped projecting tang 11, formed of companion projections 12—12' formed integral with the die members 7 and 7'. To 90 maintain the die members 7 and 7' in the same relative plane, there is formed a transverse recess or key seat 13 on the inner face of the die member 7', and a corresponding 95 spline 14 is formed on the inner face of the other die member 7, adapted to register with and to reside within the recess 13 of the die member 7'. The die members 7 and 7' as shown in assembled position in Fig. 2 are provided with a tapering annular recess 15, 100 formed centrally in its lower end and registering with the beveled face of the collar 8 of the shell 6.

Located on the walls of the annular recess 15 are sections of projecting V shaped cutting teeth 16, arranged in spiral and adapted to cut a screw thread in a manner well known in the art.

It will be apparent to those skilled in the art, that as a break occurs in any rod section 110

as at 3', the rods above the point of break may be withdrawn and the thread cutting device herein described shown assembled in Fig. 2 attached to the lower end of the last 5 section of a whole rod to be withdrawn, and the rod sections reassembled and lowered to the point where the break occurred. Upon reaching this point the beveled face of the collar 8 on the shell 6 will engage the end 3' 10 of the broken rod remaining in the well. Upon such engagement the broken end 3' will be guided in to the recess 15, until engagement is had between the broken end 3' and the thread cutting teeth 16. When this 15 point of engagement occurs the rod 3'' is caused to be turned by suitable means at the top of the well which will communicate a like movement to the thread cutting dies 7 and 7' a continuance of the turning movement described will cause a screw thread to be formed on the end of the rod 3'. When 20 a thread has been so formed by the cutting teeth, 16, the thread will register with and reside in the groove interposed between each 25 contiguous spiral teeth sections comprising the cutters 16, and form an effective screw joint, thus again joining the two lengths of rod sections that had become parted by the break. With the rod sections so joined, a 30 continuance of the pumping operation may be resumed and carried on as before the break had occurred or the whole string of rod sections may be withdrawn from the well until the newly formed joint is reached, 35 when, if desired, a whole section of rod may be positioned to replace the broken section with the newly formed joint. With my improvement, this replacement may be dispensed with until such time as the rods have 40 eventually to be withdrawn to repack the piston plunger with new suction cups. A further advantage residing in my improvement is found in its use when the pump rods are inserted into the well at the initial rod- 45 ding. The last joint projecting out of the well, when the lower end of the string has reached its lower position, may be too long or too short to position the screw joint thereon in proper registration with the pump 50 actuating means located above the mouth of the well. This often occurs at wells located some distance from industrial centers at which a rod joint of the necessary length could be manufactured. With this condition 55 at hand, the excessive length of the rod projecting above the pump actuating means may be cut off and with the application of my improvement to the severed end, suitable connection can be made with the pump 60 actuating means.

It is to be understood that I do not limit myself to the specific form of apparatus herein shown, as other forms may be used without departing from the spirit of my invention.

What I claim as new, and desire to secure by Letters Patent is:

1. A screw cutting device of the character described comprising a pump rod member, a tubular socket mounted thereon, detachable cutting dies mounted in said socket and means integral with said dies for holding against movement within the socket. 70

2. A device of the character described comprising a rotatable shaft positioned within a well, a pair of detachable thread cutting die members mounted thereon and means for rotating the die members actuated at a point above the well. 75

3. In a tool of the class described, a pair of detachable thread cutting companion dies, a tubular socket enclosing said dies, and means formed integral with said dies to maintain them against rotation within said socket and against relative movement to each 85 other. 80

4. In an apparatus of the character described comprising a well pump rod, a shank member attached to said pump rod, a tubular shell member having one end attached 90 to said shank, and formed with an inwardly extending collar on the other end, thread cutting die members positioned between the inwardly extending collar member and the shank member, and means for maintaining 95 the die members in operative position against relative movement to the shank member. 95

5. A thread cutting tool comprising a pair of companion dies, a tubular socket enclosing said dies, with means formed integral 100 with said dies to maintain them against rotation within said socket and restraining means against relative movement to each other. 100

6. In an apparatus of the character described comprising a well pumping rod, a shank member detachably connected to said rod, a tubular shell member detachably connected to said shank, thread cutting die members positioned in said shell member 110 having operative connection with said shank member. 105

7. A device of the character described comprising a well pumping rod extending into a well, a shank member connected to said rod, a tubular shell member depending from said shank member, removable companion die members positioned in said shell member having operative connection with said shank member and means integral with 115 the die members to maintain them in the same horizontal plane. 120

8. An apparatus for forming screw threads on a pump rod within a well, comprising a rotatable shaft, a die socket located on said shaft, thread cutting dies positioned in said socket, and means for centering the pump rod within said socket. 125

9. In a tool of the character described a pair of companion thread cutting dies, a tu- 130

bular socket enclosing said dies formed with a tapering opening below said dies, and means formed integral with said dies to maintain them against relative movement to each other.

5 10. An apparatus for forming screw threads on a pump rod within a well, comprising a jointed shaft extending into a well,

a tubular die socket located on the lower end of said shaft, thread cutting dies positioned within said socket against relative movement therein, and means for centering the pump rod within said socket upon engagement therewith.

In testimony whereof I affix my signature.
BURCHARD D. THOMPSON.
